FRAUD PREVENTION DEVICE

Burt R. Greenison, New York, N. Y.

Application March 7, 1935, Serial No. 9,848

2 Claims. (Cl. 215—7)

This invention relates to fraud prevention devices, and more specifically to means applied to a bottle or other container which will insure the purchaser receiving the original contents. In 5 other words, I provide an improved closure for the neck of the bottle which cannot be moved to open position without breaking a fragile connection and which when once moved to open position cannot again be returned to closed position.

10 A further object, therefore, is to provide an improved package which is in a real sense sealed and requires breakage to remove the contents.

With these and other objects in view, the invention consists in certain novel features of construction and combinations and arrangements of parts, all of which will be more fully hereinafter described and pointed out in the claims.

In the accompanying drawing—

Figure 1 is a view in vertical section illustrating my improved device in connection with a bottle;

Figure 2 is a top plan view showing in full lines the closed position and in dotted lines the open position of the upper or outer disk;

25 Figure 3 is a view similar to Figure 1, the view being taken on the line 2—2 of Figure 3; and

Figure 4 is a fragmentary view mainly in elevation and partly in section illustrating a modification.

30 I represents a bottle having the ordinary neck 2 and on the shoulder of the bottle adjacent the neck 2 I provide a fragile post 3, which is preferably of glass and constitutes an integral part of the bottle, and is molded when the bottle is formed, although the post may be otherwise formed on the bottle, as desired.

The post 3 has an annular groove or weakened portion 4 near its lower end, so that when the post is broken it will break at its weakened portion 4. 40 5 represents a cap which may be of rubber or other suitable resilient material, and which is fitted over the lower portion of the post and normally covers the weakened portion 4 of the post. This rubber cap 5 has a slotted opening 6 therein, the walls of which are expanded when the cap is inserted over the post, and when the post is broken off this cap will close and cover the exposed end of the post so as to prevent any possibility of the user injuring his hands by the 45 jagged end of the broken post.

The bottle neck 2 is closed by an inner disk 7 and an outer disk 8. These disks may be of metal or any other suitable material and are connected centrally by a rivet 9. The inner or lower disk 7 is secured to the bottle neck 2 in any approved

manner. I have shown the disk as having a depending flange 10 which may be cemented or otherwise secured to the outer face of the neck, and under this disk 7 a packing disk 11 is located and held tightly against the end of the bottle neck. This disk 11 may be of cork or any other suitable material and constitutes an air and liquid-tight closure for the bottle. The upper or outer disk 8 may also have a depending annular flange 12 which hides the inner disk and its 10 flange, and affords a sufficient surface to enable the operator to easily turn the disk.

The disks 7 and 8 have pouring openings 13 and 14, respectively, therein and these pouring openings are normally out of register. The upper or 15 outer disk 8 carries a spring-pressed plunger 15. This spring-pressed plunger 15 is mounted in an upwardly off-set pocket 16 on the disk and the plunger 15 rides against the upper face of the disk 7 and is normally out of register with a recess 20 17 of the disk 7. This recess 17 is so located that when the upper or outer disk 8 is turned to a position to register the openings 13 and 14 the plunger 15 will spring into the recess 17 and lock the outer disk against movement. Thus, when 25 20 the outer disk is turned to its open position it cannot be again turned or moved. When the outer disk is turned to register the openings 13 and 14 a suitable tool may be inserted through said openings to punch a hole in the packing disk 11 so 30 that the contents may be poured out through the registering openings.

An angle arm 18 constitutes a fixed part of the disk 8 and it may, as illustrated, constitute an integral part of the flange 12 of the disk 8. The 35 arm 18 has an opening 19 therein normally receiving the fragile post 3. Thus, it will be noted that it will be impossible to turn the disk 8 without breaking the fragile post, and this breaking may be done by the turning movement of the 40 disk or the manual breaking of the post before the disk is turned.

In the modification illustrated in Figure 4 of the drawing, I show a wire 20 which is at one end embedded in the material of the bottle, and its 45 other end is secured to the disk 8, so that this wire constitutes a fragile post or connection which must be broken before the disk can be turned to open position.

While I have illustrated what I believe to be 50 the preferred embodiment of my invention, it is to be distinctly understood that various slight changes may be made with regard to the form and arrangement of parts without departing from my invention, and hence I do not limit myself 55

to the precise details set forth but consider myself at liberty to make such changes and alterations as fairly fall within the spirit and scope of the claims.

5 5. What I claim is:

1. The combination with a bottle having a neck of a disk secured on the end of the bottle neck, an upper disk above the first mentioned disk and pivotally connected thereto at its center, said disks having openings therein normally out of register, and a concealed locking device between the disks adapted to lock the disks against independent movement when the upper disk has been turned to register its opening with the opening in the lower disk, said locking device comprising a spring-pressed plunger housed within the upper disk and said lower disk having a recess into which the plunger moves when the outer disk is turned to open position.

2. The combination with a bottle having a neck of a disk secured on the end of the bottle neck, an upper disk above the first mentioned disk and pivotally connected thereto at its center, said disks having openings therein normally out of register, a concealed locking device between the disks adapted to lock the disks against independent movement when the upper disk has been turned to register its openings with the openings in the lower disk, said locking device comprising a spring-pressed plunger housed within the upper disk and said lower disk having a recess into which the plunger moves when the outer disk is turned to open position, and a packing disk under the lower disk and adapted to have an opening punched therethrough when the openings of the first mentioned disks are in register. 5 10 15
